E. R. GILL.
SELECTIVE SIGNALING SYSTEM.
APPLICATION FILED SEPT. 18, 1909.

1,091,832.

Patented Mar. 31, 1914.

Figure 1

The diagram illustrates a selectively operated switch mechanism. A rectangular housing contains a vertical solenoid 13 with a plunger 11. A coil 27 is wound around the solenoid. A spring 15 is attached to the plunger 11. A lever system is shown: a main lever 14 is connected to the plunger 11, and a secondary lever 16 is connected to the main lever 14. A switch 17 is positioned between the main lever 14 and the secondary lever 16. A power source 18 is connected to the coil 27. A voltmeter 19 is connected in parallel with the power source 18. A label "SELECTIVELY OPERATED" is positioned above the housing.

HALL SWITCH & SIGNAL COMPANY, A CORPORATION OF MAINE.

SELECTIVE SIGNALING SYSTEM.

1,091,832.

Specification of Letters Patent. Patented Mar. 31, 1914.

Application filed September 18, 1909. Serial No. 518,390.

To all whom it may concern:

Be it known that I, EDWIN R. GILL, a citizen of the United States, residing in the city of Yonkers, county of Westchester, and 5 State of New York, have invented a certain new and useful Improvement in Selective Signaling Systems, of which the following is a specification.

This invention relates to signaling systems 10 and more particularly to such systems as are applicable to telephonic train despatching.

The present invention contemplates particularly a simple form of answer back, 15 whereby upon closing a local circuit at a distance by means of selective mechanism connected with the main circuit, the operator may be instantly apprised of the successful operation of the circuit closer.

20 Other objects will be in part obvious and in part pointed out hereinafter.

The invention accordingly consists in the features of construction, combinations of elements and arrangements of parts, which 25 will be exemplified in the construction hereinafter described, and the scope of the application of which will be indicated in the following claims.

In the accompanying drawings in which 30 are illustrated two preferred forms of various embodiments of my invention: Figure 1 is a diagrammatic view of one embodiment thereof; and Fig. 2 is a similar view of a slightly different embodiment.

35 Similar reference characters refer to similar parts in both figures of the drawings.

Referring now to the drawings, and particularly to Fig. 1, the view may be said to illustrate diagrammatically a signaling 40 device, wiring and operating device in a receiving station of a telephonic train despatching circuit. 1 and 2 respectively denote opposite sides of the main telephone line and connected in bridge thereof as by wires 3

45 and 4 is a telephone 5. Located in a bridge 6 of the main telephone line is a selector indicated diagrammatically at 7. This selector which may be of any approved type is preferably an instrument such as is described in

50 Letters Patent No. 906,523 issued to me December 15, 1908, and includes magnets 8 and 10 upon which are positioned coils 11 and 12 of the bridge 6. Impulses impressed upon the main line energizing these coils 55 effect the operation of mechanism (not

shown) to operate a circuit closer 13 which co-operates with a contact 14 to close a local circuit 15. This local circuit is provided with a suitable source of current supply as a battery 16, and has included therein an electro-magnetic signal 17 which may take the form of an ordinary electric bell. 60 18 denotes an electro-magnet and positioned thereon is a coil 20, said coil comprising a portion of the local circuit 15. In the present instance coils 21 and 22 of the local circuit are positioned upon the magnets 8 and 10 of the selector. Located in a bridge 23 of the main line is a coil 24 which is positioned upon the electro-magnet 18 thereof and is in 65 inductive relation with the coil 20 of the local circuit. It will be noted also that the coils 21 and 22 of the local circuit are in inductive relation with the coils 11 and 12 of the bridge 6. In the present embodiment 70 of my invention choke coils 25 and 26 are located in the bridge 6. The function of these coils which may be located on one or both sides of the selector is to slow down or cushion the rapidly undulating and oscillating currents such as those impressed upon telephone circuits and those due to lightning. Having described this embodiment of my 75 invention the operation thereof may now be understood.

The operation of the answer back depends upon the inductive effect of the undulatory or interrupted current set up in the local signal circuit by the direct action of the interruption which forms a part of the local 80 signal. This current passing through the coil 20 which acts as a primary, while the magnet 18 acts as a converter core, sets up by induction a corresponding alternating current in the main line by means of the 85 bridge 23. This alternating current causes a buzzing in the receiver of the train despatcher's telephone, which apprises him of the fact that the desired station has been called and the signal therein operated.

In the present embodiment of my invention coils of the local circuit 15 are shown as positioned upon the magnet 18 as well as upon the magnets 8 and 10 of the selector, and therefore said coils are in inductive relation with the coils of both the bridges 6 and 23. It will be understood of course that the coils upon the selective magnet may be omitted without in any way departing from the spirit or scope of the invention.

In Fig. 2 of the drawings the selector coil 11 is located in a bridge 27 of the main line and an electro-magnet 18 is in the same bridge and is therefore in series with the selector. A coil of the local circuit 15 is located upon the electro-magnet 18 as in the embodiment first above described.

It will be understood that when the local signal 17 is operated by the closing of the 10 local circuit 15 produced by the stepping up of the selector there will be set up by induction an alternating current in the main line which so affects the diaphragm of the despatcher's receiving instrument as to notify him that the proper station has been called and its signal operated.

It will accordingly be seen that I have provided an apparatus well adapted to attain among others all the ends and objects 20 above enumerated in a simple yet efficient manner.

As many changes could be made in the above construction and many apparently widely different embodiments of this invention could be made without departing from the scope thereof, it is intended that all matter contained in the above description or shown in the accompanying drawings shall be interpreted as illustrative and not in a 30 limiting sense. It is also to be understood that the language used in the following claims is intended to cover all of the generic and specific features of the invention herein described and all statements of the scope of 35 the invention, which as a matter of language, might be said to fall therebetween.

Having thus described my invention, what I claim as new and desire to secure by Letters Patent is:

40 1. A signaling system comprising a main line, selective mechanism connected to said main line, a local circuit including an electro-magnetic signal, a circuit closer for said local circuit adapted to be operated by said 45 selective mechanism, an electro-magnet, said local circuit having a coil on said electro-magnet, and a second coil on said magnet connected with the main line.

2. A signaling system comprising a main line, selective apparatus connected to said main line, a local circuit including an electro-magnetic signaling device, an electro-magnet, a coil in said local circuit located upon said electro-magnet, a coil upon said electro-magnet connected in bridge of the 55 main line, and a circuit closer operated by said selective mechanism for closing said local circuit.

3. A signaling system comprising a main line, selective mechanism connected in bridge 60 of the line, a local circuit comprising an electro-magnet and an electro-magnetic signal, said local circuit having a coil upon said electro-magnet, and a second coil upon said electro-magnet connected in bridge of 65 the main line.

4. A signaling system comprising a main line, a selective signal operator having coils connected in bridge of the main line, an electro-magnet, an electro-magnetic signaling device, a local circuit for said signaling device including one or more coils on said electro-magnet, a second coil upon said electro-magnet connected with the main line, and means for closing said local circuit arranged to be operated by said selective signal operator.

5. A signaling system comprising a main line, a selective signal operator having coils connected in bridge of the main line, 80 an electro-magnet, an electro-magnetic signaling device, a local circuit for said signaling device including a coil on said electro-magnet and one or more coils located in inductive relation with the coils of the selective signal operator, a second coil upon said electro-magnet connected in bridge of the main line, and means for closing said local circuit arranged to be operated by said selective signal operator.

In witness whereof I affix my signature in the presence of two witnesses.

EDWIN R. GILL.
